CLASSIFIER FOR DRY IMPALPABLE FINES

Paul Gerhardt, Staley, N. C., assignor of one-half to William G. Broadfoot, Wilmington, N. C.

Application December 24, 1936, Serial No. 117,640

4 Claims. (Cl. 209—139)

This invention relates to improvements in classifiers of that type which effect centrifugal separation of dry crushed or powdered substance into two or more grades.

One of the recognized inherent drawbacks in the operation of centrifugal classifiers is that while they do separate the impalpable fines from the coarser granules, they are unable to deliver the impalpable fines segregated from the next coarser grade.

It will be understood by those skilled in the art that centrifugal force acts to throw the heavier particles outward and as a result of the outward displacement of the heavier particles, the lighter particles remain in the less disturbed area toward the center of rotation of the centrifugal mechanism, the portion of the powdered substance which is of impalpable fineness being suspended in the atmosphere around the axis of rotation, there being no way to get it out so that as it increases in density it is entrained in the flow of larger particles, being carried outward by centrifugal force, being discharged in mixture with the particles of next coarser grade.

Regardless of how many grades of material the centrifugal classifier is capable of separating, the fact remains that the finest grade delivered is a mixture including the impalpable powder or dust which would form a grade to itself providing the centrifugal classifier were able to separate it out.

The object of the present invention is to remove the impalpable fines from the region adjacent the axis of the centrifugal mechanism of a classifier of this type and to deliver it as a grade separate and distinct from the grades which the classifier is normally able to deliver, this being accomplished by means which form the subject matter of the following specification and being illustrated in the drawing accompanying and forming a part of the same.

Other objects of the invention will appear as the following description of a preferred and practical embodiment thereof proceeds.

In the drawing which illustrates a practical embodiment of my invention:

Figure 1 is a vertical section through a centrifugal classifier embodying the features of my invention; and

Figure 2 is a cross section taken along the line 2—2 of Figure 1.

Before advertizing to a description in detail of the illustrative mechanism it may be stated that there are a number of structurally different centrifugal separators, any of which may be em-

ployed as an element in my novel combination, the one herein illustrated being of well known construction and selected by reason of its simplicity. It comprises an outer casing 1 having a cylindrical upper portion 2 and a conical lower portion 3. The lower portion has a discharge 4.

Within the cylindrical portion of the outer casing 1 is a cylindrical baffle 5 of smaller diameter than the outer casing defining an annular chamber 6. Within the conical lower portion 3 of the casing 1 is a cone 7 open at its upper end 8 and having a discharge 9. The baffle 5 and cone 7 are spaced apart as at 10 forming an air entrance which is guarded by an annular series of bars 11. The baffle 5 is spaced below the top wall 12 of the outer casing 1 forming an air space in which works a fan 13 mounted on a hollow shaft 14 which extends to a point outside of the casing 1 and has a driving gear 15, by means of which the shaft 14 and fan 13 are rotated. The baffle 5 is provided with an inwardly extending annular flange 16 beneath the blades of the fan 13, leaving a central opening 17 beneath the central portion of the fan. On the bottom of the rotating shaft 14 a circular distributing device 18 is positioned, said distributing device comprising spaced plates 19 and 20. A fixed tube 21 extends through the hollow shaft 14 and discharges on to the plate 20. At the upper end of the fixed tube 21 is a funnel 22. Material to be classified is poured in through the funnel 22, lands on the rotating plate 20 from which it is thrown out by centrifugal force, the larger particles striking the inner wall of the baffle 5 and falling by gravity into the cone 7, passing out through the discharge 9.

The fan 13 creates an air current which flows downward through the annular chamber 6 and which passes through the spaces 23 between the bars 11 and flows upwardly under the suction of the fan 13. Since the discharge 4 is open some of the air current from the pressure side of the fan divides and passes downward through the space between the cone and the conical portion of the outer casing. That part of the material thrown outwardly by the plate 20 and which does not immediately gravitate down into the cone 7 is intersected and entrained by the upwardly flowing current and carried into the path of the fan where it is thrown outwardly into the annular chamber 6 and travels down the space between the cone and lower portion of the outer casing in a vehicle of moving air and is finally discharged at the point 5.

It will be understood that conventional struc-

ture is now being described in which the revolving gate 24 is not present so that the discharge 4 is freely open. The displacement of air laden with the heavier solid matter in an outward direction through centrifugal force by the fan 13 causes a contra-displacement of the air laden with the impalpable dust in an inward direction, the dust remaining in suspension in what may be termed an inert core of air occupying the central part of the baffle 5 and bounded on the outside by the upward air flow from the bottom of the baffle 5 to the fan. In conventional structure there is no means for removing this suspension as a segregate entity so that as it becomes added to from the top by the action of the fan, it is dissipated laterally by being entrained in the upwardly directed air currents and passes outwardly through the fan down through the chamber 6 and through the space between the cone 1 and the lower portion 3 of the outer casing, being impelled by that part of the air current which flows through the space between the cone and the lower portion of the outer casing.

It is the object of the present invention continually to withdraw this central suspension of impalpable fines. With this end in view provision is made for rarefying the air in the central region of suspension. This reduces the particle-supporting capacity of the air and the larger particles of suspended matter gravitate downward into the cone 1. Means are provided for creating an upward air flow to draw the suspended matter out of the apparatus without permitting it to become mixed with any of the grades of less fineness. Such means comprises in the present illustrated embodiment of the invention, a hood 25 positioned on top of the outer casing 1 and having an inverted mouth 26 of considerable width so that it will promote an upward drift of the suspension atmosphere rather than a jet of the same. The mouth is defined by a downwardly projecting flange 27 extending as close as practicable to the fan 13. The hood is in communication by way of a conduit 28 with an exhaust fan chamber 29 housing a suitable exhaust fan 30 which sucks from the hood and delivers to a cyclone collector or other similar apparatus not shown.

Within the hood the shaft 14 is provided with blades 31 pitched in a direction and at such an angle as to cause the upward drift of the suspended matter referred to. The hood is preferably bevelled at the top as shown at 32 bringing the wall of the hood close to the path of the blades 31 avoiding inert pockets of dust-laden air and facilitating the displacement by the blades 31 of suspended matter rising on the side of the hood remote from the conduit 28.

With the end in view of collecting all of the impalpable suspended matter, it is desirable that no portion of the air current flowing downwardly through the annular chamber 6 should be diverted into the space between the cone 1 and the lower portion 3 of the outer casing 1, for as has been stated, such air current carries with it some of the impalpable matter in addition to the fines which are ordinarily delivered through the discharge 4. In order to prevent this diversion of a part of said air current, the gate 24 is provided, which comprises a casing 33 having an opening in one end registerable with the discharge 4 and an outlet opening 34. A driven shaft 35 rotates at a predetermined speed within said casing carrying vanes 36, the outer ends of which revolve in substantial engagement with a cylind-

rical intermediate part of the casing 33. The blades 36 are so spaced that in any position of the shaft 35 they block the passage of an air current through the discharge 4. The fines which the discharge 4 is designed to deliver fall by gravity into the pockets between the blades as said pockets are successively presented to the discharge 4 and by the rotation of the pockets they are dumped through the outlet 34. In view of the blocking of air flow through the discharge 4, a body of inert air remains in the space between the cone 1 and the lower portion 3 of the outer casing. This means that the entire current after having dropped the coarser fines at the point where its velocity is checked against the bars 11, returns upwardly within the cylindrical baffle 5 carrying all of the impalpable fines which by the contra-displacement produced by the centrifugal action of the fan 13 pass into the central inert region of the classifier where they are drawn upwardly in the manner already described and taken out by the exhaust fan 30.

The discharge 9 is also preferably controlled by means of a similar gate 37 having vanes 38 blocking the passage of air currents through the discharge 9 preventing the diversion of any part of the fines-laden current through said discharge. The gates 24 and 37 may be speed controlled.

It will of course be understood that the pull of the blades 31 rarefies the air in the central portion of the classifier so that it is no longer able to support the heavier particles in the suspended matter which particles descend by gravity into the cone 1 and out by way of the discharge 9 so that only the finest powder is withdrawn by the exhaust fan 30. The degree of fineness of the impalpable fines may be regulated by varying the speed of the exhaust fan 30. When the exhaust fan is speeded up, the suction in the central region of the classifier is increased thereby robbing the lateral upwardly flowing current of more or less of the grosser particles which it is carrying.

While I have in the above description defined what I believe to be a preferred and practical embodiment of my invention, it will be understood to those skilled in the art that the details of construction as illustrated and described are merely by way of example and not to be construed as limiting the scope of the appended claims.

What I claim is:

1. Classifier for dry comminuted substance comprising a casing, means within said casing defining therewith inner and outer chambers, the inner chamber communicating both above and below with the outer chamber, a centrifugal fan creating a circuitous air current up through the inner chamber and down through the outer chamber, a centrifugal distributor in the lower part of the inner chamber obstructing the central part of said chamber, thereby diverting the said air current, making it flow close to the wall of said inner chamber and leaving the atmosphere in the central part of said inner chamber above said obstructing means inert, means for feeding ungraded material on to said distributor whereby it is spread centrifugally in said air current, means providing separate paths of exit for tailings and intermediate fines, the tailings dropping by gravity into one path, the fines being carried by said current into the path of said fan, the latter member throwing out the heavier granules in the other path of exit, the substantially impalpable particles by contra-centrifugal dis-

placement being moved into the inert central part of the inner chamber, means for simultaneously rarefying the atmosphere in said central part, causing the gravitational drop of the heavier particles of suspended matter, and drawing the remaining suspended impalpable fines out through an independent exit.

2. Classifier for dry comminuted substance comprising a casing having an upper separating portion and a lower receiving portion, an annular open ended baffle within said upper portion defining with the adjacent part of said casing inner and outer chambers, a receiving member for tailings below and spaced from the lower end of said baffle, and spaced from the receiving portion of said casing forming a passage for intermediate fines, said receiving chamber and passage having independent outlets, said inner chamber communicating both above and below said baffle with the outer chamber, a centrifugal fan creating a circuitous air current up through the inner chamber and down through the outer chamber, a centrifugal distributor in the lower part of the inner chamber obstructing the central part of said chamber thereby diverting the said air current, making it flow close to the wall of said inner chamber and leaving the atmosphere in the central part of said inner chamber above said obstructing means inert, means for feeding ungraded material on to said distributor whereby it is spread centrifugally in said air current, the tailings dropping by gravity into said receiving member and the intermediate fines being carried by said current into the path of said fan, the latter member throwing out the heavier granules into the outer chamber from which they descend into said passage, the substantially impalpable particles by contra-centrifugal displacement being moved into the inert central part of the inner chamber, means for simultaneously rarefying the atmosphere in said central part, causing the gravitational drop of the heavier particles of suspended matter, and drawing the remaining suspended impalpable fines out through an independent exit, and a gate controlling the dis-

charge of intermediate fines from said passage while inhibiting unrestricted air flow through said passage, diversion of any substantial part of said air current through said passage being thus inhibited or controlled.

3. Classifier for dry comminuted substance comprising a casing, an annular baffle within said casing defining therewith inner and outer chambers, the inner chamber communicating both above and below with the outer chamber, a centrifugal fan creating a circuitous annular air current up through the inner chamber and down through the outer chamber, a centrifugal distributor in the lower part of the inner chamber obstructing the central part of said chamber, thereby diverting the said air current making it flow close to the wall of said inner chamber and leaving the atmosphere in the central part of said inner chamber above said obstructing means inert, means for feeding ungraded material on to said distributor whereby it is spread centrifugally in said air current, means providing separate paths of exit for tailings and intermediate fines, the tailings dropping by gravity into one path, the fines being carried by said current into the path of said fan, the latter member throwing out the heavier granules into the other path of exit, the substantially impalpable particles by contra-centrifugal displacement being moved into the inert central part of the inner chamber, forming a dome above said casing and in communication with said central part of the inner chamber, a conduit communicating with said dome providing a discharge separate from the aforementioned paths of exit, a suction fan in said conduit, and means in said dome for rarefying the atmosphere in the central part of said inner chamber and for drawing the suspended matter upward into said dome and toward the mouth of said conduit.

4. Classifier as claimed in claim 3, said rarefying means including pitched blades rotatable unitarily with said centrifugal distributor.
